UNITED STATES PATENT OFFICE.

FREDERICK HACHMANN, OF ST. LOUIS, MISSOURI, ASSIGNOR, BY DIRECT AND MESNE ASSIGNMENTS, OF ONE-FOURTH TO JOHN A. DOWDALL AND ONE-FOURTH TO BERNARD GREENSFELDER, BOTH OF ST. LOUIS, MISSOURI, AND ONE-HALF TO NATIONAL METAL DIE MOLD COMPANY, OF ST. LOUIS, MISSOURI, A CORPORATION OF MISSOURI.

CASTING METHOD.

1,356,713.

Specification of Letters Patent. Patented Oct. 26, 1920.

Application filed April 2, 1917, Serial No. 159,236. Renewed May 13, 1920. Serial No. 381,192.

To all whom it may concern:

Be it known that I, FREDERICK HACHMANN, a citizen of the United States, and residing at St. Louis, Missouri, have invented the new and useful Improvement in Casting Methods, of which the following is a specification.

This invention relates to a casting method and apparatus, and more particularly to a method and apparatus for casting metals, such as brass, bronze and other copper alloys.

In casting metals of the higher melting points, it is the present practice to use sand or loam molds which are, of course, vented in order to insure the escape of gases, such as air, etc. With such molds, there must necessarily be allowed a good deal of draft in order to permit withdrawal of the pattern from the mold, and there must also be allowed considerable finish in order to take care of pits and blowholes. The result therefore, is that the casting is necessarily considerably oversize, which means waste in metal, fuel, labor and the incidental expense of machining.

Various attempts have been made to use metal molds in order to obviate the draft and finish, and the resultant wastage always present in using sand and loam molds. Such attempts have, however, been in the main, unsuccessful, except with metals of low fusing points, which permit the application of pressure to form what are called die castings. It is, however, impractical to cast metals of the higher melting points, such as brass, bronze, and other alloys of copper, in metal molds; this difficulty is particularly due to the impossibility of withdrawing the air and other gases from the mold cavity during the casting operation, so that the resultant casting will be full of pits and blowholes. Moreover, these higher melting point metals will adhere or solder to the mold, so that the separation of the casting from the mold is difficult and often an impossibility, except where the casting or mold, or both, are destroyed.

Some of the objects of this invention, therefore, are to provide a casting method and apparatus in which the withdrawal of the air and other gases from the mold cavity is insured, and in which the walls of the mold cavity are treated in such a manner as to prevent adhesion of the material, to cast, to the mold.

Further objects will appear from the detail description taken in connection with the accompanying drawings, in which:

Figure 1 is a plan of a mold embodying this invention;

Fig. 2 is an elevation of one of the mold sections, the view being taken on the line 2-2, Fig. 1;

Fig. 3 is a section on the line 3-3, Fig. 1; and,

Fig. 4 is a reduced perspective of the casting.

In accordance with this invention, the gases are withdrawn from between the material poured into the mold and the walls of the mold, below the surface of the material accumulated in the mold, and as it accumulates. This is done by venting passages which vent the mold cavity at numerous points, but these venting passages are constructed to avoid flowing of the cast material therein. The mold cavity walls are treated to prevent adhesion thereto of the material to be cast. This is effected by applying to the mold wall, a lubricant, such as a high flash point oil. In order to maintain this lubricant on the cavity walls, there are employed a series of lubricant conducting passages or channels, which deliver the lubricant at numerous points on the cavity walls. The lubricant is maintained in a source of supply which contains a retaining vehicle holding the lubricant by an absorbent action, so that the lubricant will be delivered at a very low pressure to the cavity walls. These passages, as is the case of the venting passages, are made small enough to avoid flowing of the cast material therein. As the lubricant is necessarily somewhat volatile even where a high flash point oil is

used, the venting passages are arranged adjacent to the lubricant supplying passages, so as to carry off any gases which may be formed.

5 Referring now to the accompanying drawing, the mold, as shown, is formed of two sections, each formed of a series of blocks 1, the blocks of a section being securely clamped and bolted together by bolts 2 and 10 nuts 3. These mold sections are adapted to be placed in alined relation by dowels 4 in one section, coöperating with holes 5 in the other section. Each mold section has formed therein, one or more parts of mold 15 cavities 6, of a shape to form the desired casting. In order to furnish a gate, the sections are recessed as shown at 7.

The mold sections are cut to form a channel 8, extending along the mold, and from 20 these channels extend branches 9, these branch channels 9 extending upwardly, and being arranged along the mold cavity, one-half of each branch being formed in each section of the mold, as shown in Fig. 2. 25 Connecting the mold cavity with the channels 8 and 9, are a series of venting passages 10, each cut in one-half of the mold section, as shown in Fig. 2. These venting passages 30 10 are small and form, in fact, capillary passages, in that, while they permit discharge of gases, they do not permit flow of the metal therein, to more than an infinitesimal amount. These passages 10 are for the purpose of withdrawing the air from the mold 35 during the casting operation, and in order to obtain the best results, these passages preferably incline or extend downwardly from the mold cavity to the outlet channels.

40 Arranged laterally of and extending along a mold cavity, are a pair of pockets 11, which are filled with a lubricant retaining vehicle adapted to absorb and retain the lubricant. A material which is found 45 to satisfactorily answer this purpose is a granular porous carbon containing no graphite, and in pieces about the size of a match head. The mold cavity is connected with these pockets by means of capillary 50 lubricant conducting passages, which are cut in the faces of the blocks before they are put together. In order to obtain a gravity flow, the passages 12 are preferably inclined or extend downwardly from the 55 pockets to the mold cavity. It will be noted that both the venting passages 10 and the lubricant conducting passages 12, enter the mold cavity at numerous points, and that the venting passages are, therefore, closely 60 adjacent the lubricant conducting passages. It will also be noted that, as is the case with the venting passages 10, the lubricant conducting passages 12, are of small diameter, so as to avoid flowing of the metal therein.

It is necessary that the mold be hot during the casting operation, and it is desirable that this heat should be maintained uniform. In order to provide for such heating means, there is provided on each section, an electrical resistance heating element 13, of 65 any suitable construction, each element being connected by terminals 14, to a source of current. In order to retain this element in place, plates 15 are provided, which are screwed to the mold by screws 16. It will, 70 of course, be understood that the resistance heating element 13 is suitably insulated from the mold and the mold section, and from the plate 15.

When a casting is to be made, the filling 80 in the pockets 11 is saturated with a lubricant, such as a high flash point mineral oil, and the walls of the mold cavity have also preferably applied thereto, in any suitable manner, a film of this oil. It will, of course, 85 be understood that the mold has first been heated up to a sufficiently high temperature by current traversing the heating element. The metal is now poured into the mold in the usual manner, and as it flows into the 90 mold cavity, the air and gases escape through the venting passages 10. Moreover, any volatilized oil will escape through these same venting passages 10, as their position close to the lubricant conducting passages, and their numerous outlets to the surface of the mold, will quickly insure the withdrawal of any gas which may be formed or which may be present during the casting operation. The casting will, therefore, 95 be free from pits and blowholes. The film of oil on the mold cavity walls, will prevent adhesion of the metal to the mold, and the supply of lubricant to the mold cavity walls is continually supplemented by 100 the lubricant conducting passages 12 leading from the sources of lubricant supply in the pockets 11. Adhesion of the metal to the mold is, therefore, avoided. Furthermore, 105 the presence of this lubricant has the tendency to give a smooth finish surface on account of the formation of carbon, so that smooth castings are obtained.

It is obvious that various changes may be made in details of construction without departing from the spirit of this invention. It is, therefore, to be understood that this invention is not to be limited to the specific details described and shown.

Having thus described the invention, what 110 is claimed is:—

1. The method of casting in a mold having metallic mold walls, comprising supplying a quantity of lubricant to the metallic walls of the mold through the said walls to 115 prevent adhesion thereto of the material to be cast, and pouring the material to be cast into the mold and at the same time allow-

ing the gases to escape from the mold through the metallic walls of the mold.

2. The method of casting in a mold having metallic mold walls, comprising supplying a quantity of lubricant to the metallic walls of the mold through the said walls to prevent adhesion thereto of the material to be cast, and pouring the material to be cast into the mold and at the same time allowing the gases to escape from the mold through the metallic walls of the mold below the level of the accumulated material within the mold.

3. The method of casting in a mold, which comprises supplying a quantity of carbon forming fluid to the wall of the mold cavity through the mold wall, and pouring molten metal into said mold cavity after the carbon forming fluid has been supplied to the surface of the mold cavity.

4. The method of casting in a mold, which comprises supplying a quantity of carbon forming fluid to the wall of the mold cavity through the mold wall, pouring molten metal into said mold cavity after the carbon forming fluid has been supplied to the surface of the mold cavity, and permitting the gases to escape from the mold cavity below the level of the material as the material accumulates within the cavity.

5. The method of casting in a mold having metallic mold walls, comprising treating the walls of the mold with a lubricant to prevent adhesion thereto of the material to be cast, and pouring the material into the mold while continuously supplying the lubricant to the walls of the mold below the level of the material as it accumulates in the mold.

6. The method of casting in a mold having metallic mold walls, comprising treating the walls of the mold with a lubricant to prevent adhesion thereto of the material to be cast, pouring the material into the mold while continuously supplying the lubricant to the walls of the mold below the level of the material as it accumulates in the mold.

7. The method of casting in a mold having metallic mold walls, comprising pouring the material into the mold, and applying to the walls of the mold during the pouring of the material a lubricant to prevent adhesion of the material to the mold.

8. The method of casting in a mold having metallic mold walls, comprising pouring material into the mold, and supplying continuously to the walls of the mold at various points around the surface thereof during the pouring of the material a lubricant to prevent adhesion of the material to the mold walls.

9. The method of casting in a mold hav-

ing metallic mold walls provided with lubricant supply passages through the walls thereof, comprising applying to the walls through said passages a lubricant to prevent adhesion of the material to the mold, and pouring the material into the mold.

10. The method of casting in a mold having metallic mold walls provided with lubricant supply passages through the walls thereof, comprising applying to the walls of the mold through said passages, during the pouring of the material, a lubricant to prevent adhesion of the material to the mold, and pouring the material into the mold.

11. The method of casting in a mold having metallic mold walls provided with lubricant supply passages through the walls thereof, comprising applying to the walls through said passages a lubricant to prevent adhesion of the material to the mold, pouring the material into the mold, and forcing the gases from within the mold through the mold walls below the level of the material as it accumulates in the mold.

12. The method of casting in a mold having metallic mold walls provided with lubricant supply passages through the walls thereof, comprising applying to the walls of the mold through said passages during the pouring of the material a lubricant to prevent adhesion of the material to the mold, pouring the material into the mold, and forcing the gases from within the mold through the mold walls below the level of the material as it accumulates in the mold.

13. The method of casting metals in a mold having metallic mold walls, comprising applying a lubricant to the inner surface of the mold walls through the walls of the mold cavity, pouring the metal into the mold cavity and venting the mold cavity at various points below the level of the metal accumulated in the mold, whereby the gases pass from the mold cavity below the level of the metal accumulated in the mold.

14. The method of casting metals, comprising pouring the metal into the mold cavity, maintaining a lubricant outside of the mold cavity and in communication with the cavity whereby the lubricant is supplied to the walls of the mold cavity to prevent adhesion of the metal thereto, and venting the mold cavity at numerous points below the level of the metal accumulated in the mold.

15. The method of casting in a mold of metal or the like, comprising pouring the material, while in a fluid condition, into a mold, and forcing the gases from the mold below the surface of the material accumulated in the mold, and at the same time maintaining a lubricant outside of the mold and in communication with the mold cavity whereby the lubricant is supplied to the

walls of the mold while the gases are being forced therefrom.

16. The method of casting in a mold of metal or the like, comprising pouring the material, while in a fluid condition, into a mold, and forcing the gases from the mold below the surface of the material accumu-

lated in the mold as the fluid accumulates in the mold, and at the same time supplying a lubricant to the walls of the mold below the 10 level of the material accumulated therein.

In testimony whereof I affix my signature this 31st day of March, 1917.

FREDERICK HACHMANN.
